Des. 242,467
Patented Nov. 23, 1976

242,467

FRONT PANEL FOR A COMPUTER CONSOLE

Paul A. Jenkins, Groton, Mass., assignor to Digital Equipment Corporation, Maynard, Mass.

Filed Mar. 6, 1975, Ser. No. 555,916

Term of patent 14 years

Int. Cl. D14—02
U.S. Cl. D26—5 C

FIG. 1

FIG. 2

FIG. 3

FIG. 4

FIG. 5

FIG. 1 is a front prospective of a front panel for a computer console showing my new design;

FIG. 2 is a front elevational view thereof;

FIG. 3 is a right side elevational view thereof;

FIG. 4 is a left side elevational view thereof; and

FIG. 5 is a top plan view thereof.

The portions of a computer console shown in broken lines in FIGS. 1, 3, 4 and 5 are for illustrative purposes only and form no part of the claimed design.

I claim:

The ornamental design for a front panel for a computer console, substantially as shown and described.
